Primary Examiner — Barbara Fox*Assistant Examiner* — Dana K Weiland(74) *Attorney, Agent, or Firm* — Finnegan, Henderson, Farabow, Garrett & Dunner LLP(57) **CLAIM**

The ornamental design for a display screen with animated graphical user interface, as shown and described.

DESCRIPTION

FIG. 1 is a front view of a first image of a display screen with animated graphical user interface showing the new design; FIG. 2 is a front view of a second image of FIG. 1; FIG. 3 is a front view of a third image of FIG. 1; and, FIG. 4 is a front view of a fourth image of FIG. 1.

The appearance of the transitional image sequentially transitions between the images shown in FIGS. 1-4. The process or period in which an image transitions to another image forms no part of the claimed design.

The broken lines of uneven length depict the display screen and form no part of the claimed design. The broken lines of even length depict portions of the display screen with animated graphical user interface that form no part of the claimed design.
